UNITED STATES PATENT OFFICE.

MAX J. LIEBENSTEIN AND LEO H. EMSHEIMER, OF CHICAGO, ILLINOIS, ASSIGNEES TO
A. STEIN & COMPANY, OF CHICAGO, ILLINOIS, A CORPORATION.

CLOTHING-PROTECTOR.

1,191,200.

Specification of Letters Patent. Patented July 18, 1916.

Application filed April 28, 1914. Serial No. 834,943.

To all whom it may concern:

Be it known that we, MAX J. LIEBENSTEIN and LEO H. EMSHEIMER, citizens of the United States, and residing at Chicago, in the county of Cook and State of Illinois, have invented certain new and useful Improvements in Clothing-Protectors, of which the following is a full, clear, and exact description, reference being had to the accompanying drawings, forming part of this specification.

One object of our invention is to provide a clothing protector adapted for use with modern dresses now worn and especially designed to be worn underneath bloomers.

A further object is to provide a clothing protector which will be compact and will conform closely to the outlines of the figure without forming any unsightly or uncomfortable bulges.

Still another object of the invention is to provide a clothing protector provided at its lower portion with garters that serve to sustain the stockings and hold down the protector.

The invention consists in the various features of improvement, hereinafter set forth, illustrated in the accompanying drawing and more particularly pointed out in the claims at the end of this specification.

Figure 1, is a view of our preferred form of clothing protector shown in front perspective, with the outline of the wearer shown in dotted lines. Fig. 2 is a sectional portion showing the construction of the upper corner of the garment.

The main body portion or protective apron 1, is preferably made of one piece and of some moisture proof material. The lower end of this portion has a part cut away as at 2 to form separate leg sections and the lower ends are gathered and secured to circular garters 3. These garters are of ordinary construction and have snaps 4 to facilitate in securing them around the leg and avoid the necessity of putting the feet through them. The garters are adapted for use either above the knee or below as shown in Fig. 1. The upper end of the protective apron 1 is supported by the vertical straps 5 preferably five in number, depending from a belt 6 adapted to encircle the waist. A light cloth mesh 7 is gathered and secured to the straps 5 and belt 6 and upper edge 55 of the protective apron. The purpose of this

construction is to provide a means for supporting the upper edge of the protective apron 1 and at the same time permit of a certain amount of elasticity to prevent any binding on the movements of the wearer. 60

In order to avoid all danger of the garment tearing under the strain to which it is subjected because of its closely fitting the body of the wearer, it is reinforced at the points of greatest strain in the manner next 65 to be described.

Straps 10 extend between the corners of the leg portions of the protective apron and garters, and at such point, portions of the garment are cut away. These straps 10 70 prevent the apron from being torn from the garter. Another strap 11 is provided a short distance below the crotch and extends between the upper parts of the leg portions, thus preventing the apron from being torn 75 when the legs are spread apart.

From the foregoing it will be seen that by our invention a clothing protector is provided that is adapted to extend across the seat and upper leg portions of the wearer 80 and which fits very snugly to the figure. It has been found that the ordinary apron now used is very bungling and cumbersome, especially when the wearer uses bloomers instead of the ordinary skirt. With the construction 85 herein provided, the protective apron is at all times securely held down and fastened to the legs of the wearer, and prevented by the garters from riding up. A further feature or advantage is that of providing a water 90 proof and moisture proof material to cover the parts where such a protection is needed and to provide a thin porous material where such a protection is not desired. Free movement of the wearer is permitted by the elastic nature of the upper construction so that in stooping over or sitting down, the upper portion readily stretches and does not bind. 95

Having thus described our invention, what we claim as new and desire to secure by Letters Patent, is:

1. A clothing protector comprising a protective apron having its lower portion divided to form separate leg sections open at the front, said apron above said leg sections being adapted to extend across the seat of the wearer from a point some distance below the waist to approximately the knees, the vertical front edges of said apron being adapted to extend along the sides of the 110

wearer's legs, a waist belt to the back and side portions of which the apron is connected, and leg encircling bands the rear portions of which are fastened to the separate leg sections to cause said sections to conform to the back portions of the wearer's legs.

2. A clothing protector comprising a protective apron formed of a single sheet of moisture proof material, having a portion cut away at its bottom to form separate leg sections, garters attached to said leg sec-

tions, said apron being adapted to extend from the knees of the wearer to a point at a distance below the waist line, a belt for encircling the wearer's waist, straps extending downwardly from the sides of the belt to the upper corners of the protective apron, and a strap extending between the leg sections. 15
